UNITED STATES PATENT OFFICE.

ERNST F. NORTEMAN, OF ATTLEBOROUGH, MASSACHUSETTS, ASSIGNOR TO
FRANCIS S. BAILEY, OF SAME PLACE.

DESIGN FOR A WATCH-CHAIN ATTACHMENT OR END PIECE.

SPECIFICATION forming part of Design No. 11,665, dated March 2, 1880.

Application filed January 27, 1880. Term of patent 24 years.

To all whom it may concern:

Be it known that I, ERNST F. NORTEMAN, of Attleborough, in the county of Bristol and State of Massachusetts, have invented a new and useful Design for Chain-Tips; and I do hereby declare that the following is a full, clear, and exact description of the same.

My invention is a design for an attachment or end piece for watch-chains; and it consists, essentially, in forming the same in the shape of a horseshoe.

Referring to the drawing, *a* *a* represent the chain, and *b* the attachment. This may be made in any of the well-known ways, and may be ornamented either by engraving or with a stone setting, and of any of the materials ordinarily used for such articles. The ends of the chain are attached to the ends of the horseshoe by holding-rings, and a ring-connection, for attach-

ment of a watch or other article, is applied at 20 the center of its bend.

It is evident that the ornamental attachment may be applied as a pendant for neck-chains, as well as to vest-chains, as before described.

Having described my invention, I claim—

The design for a watch-chain attachment or end piece, consisting of the device *b*, having the configuration of a horseshoe, substantially as described, and shown in the accompanying 30 drawing.

In testimony whereof I have signed my name to this specification in the presence of two subscribing witnesses.

ERNST F. NORTEMAN.
